BANDING TOOL

Charles T. Fisher, near Girard, Ohio

Application January 21, 1941, Serial No. 375,242

2 Claims. (Cl. 254—51)

This invention relates to a banding tool and more particularly to a banding tool designed for use in banding coils of strip steel.

The principal object of the invention is the provision of an efficient tool by means of which one man can effectively position, tighten, and seal a band about a coil of strip steel.

A further object of the invention is the provision of a banding tool capable of use in banding stacks of steel sheets and various other rectangular packages.

A still further object of the invention is the provision of a banding tool in which the sealing die used may be readily interchanged.

A further object of the invention is the provision of a banding tool capable of tightening the banding material, effecting the seal of the banding material, and cutting the surplus band necessarily used in effecting the tightening operation.

The banding tool shown and described herein has been designed to provide an efficient tool for applying metal bands to coiled strip steel, in as much as a large percentage of the present day steel plant capacity comprises hot rolled strip commonly shipped in coils. At the present time most of the coils are not banded due to the inefficiency of the known banding methods and means for effecting the banding operation, with the result that partial uncoiling of many of the coils of strip steel results in damage to several feet of material of each coil which must subsequently be removed and discarded as it is marred, torn, scratched, or otherwise unsuitable for use in subsequent fabricating operations. This represents a considerable waste when it is considered that the shipment of steel strip in coil form is a common practice. The trailing ends of the coils are also often damaged in intermill shipment with the result that a considerable waste occurs before the actual shipment of the coil. The principal object of the present invention, therefore, is to provide a banding tool which may be operated by one man and which will effectively and conveniently and easily apply metal bands to the coiled strip steel; tightening, sealing, and cutting off the excess band in almost simultaneous operations. The tool is particularly adapted for banding hot coil wherein the coil, while having lost its glowing color, is still of a temperature too high to permit a man to come in close contact as is necessary with the various banding tools now known to the art for the application of a band to the hot coil. The present

invention, therefore, comprises a tool which permits one man to conveniently and easily place a preformed loop of banding material about the hot coil, tighten it, seal it, and remove the excess material with the banding tool which is first used as a carrier in placing the preformed band about the hot coil.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

The invention is illustrated in the accompanying drawing, wherein:

20 Figure 1 is a top plan view of the banding tool, with parts broken away.

Figure 2 is a side elevation of the banding tool, with parts broken away.

25 Figure 3 is an end elevation taken on lines 3—3 of Figure 2.

By referring to the drawing and Figures 1 and 2 in particular it will be seen that a banding tool, comprising a slightly arched base 10, has positioned upon the upper surface thereof a body member 11 which in turn is provided at the points adjacent its opposite ends with two rotatable shafts, one of these rotatable shafts taking the form of a slotted tightening roll 12 adapted to receive one end of a band B, as shown in Figure 2, in the slot thereof in a manner so that upon rotation the tightener roll 12 causes the band to be tightened with respect to a loop formed by the band. In order to facilitate the easy placement of the end of the band B in the slot of the slotted tightener roll 12, a portion 12A of the roll 12 is cut away from the remainder and hinged thereto. This causes the tightener roll 12 to form in effect a projection positioned beside the hinged portion 12A and spaced slightly therefrom so as to form in effect an extension of the slot in the tightener roll 12. A concave section 14 is formed in the body portion 11 at one side of the tightener roll 12 so that the hinged portion 12A thereof can be moved sidewardly and backwardly thereinto when the tightener roll 12 is in appropriate position. As best shown in Figure 1 of the drawing, this hinged section 12A of the roll 12 can be swung sidewardly away from the remainder of the roll when the tightener roll 12 is in appropriate position and thus permits the end of the

band B to be easily positioned in the slot. Due to the fact that the pivot 13 of this hinged section is positioned back within the body portion 11, the hinged section 12A will automatically close once the roll 12 is rotated. This action takes place because the rounded surface above the hinged section slides against the concave portion 14 in a cam-like action as the tightener roll 12 is revolved. The concave portion 14 of the body portion 11 provides space for the hinged section 12A to swing sidewardly and backwardly into. It will thus be seen that the band B, taking the form of a loop of sufficient diameter to enclose a coil of strip steel, has its opposite ends positioned in the banding tool as best shown in Figure 2 wherein one end of the band B is shown bent backwardly over a beveled section 10A of the base 10, and passed over the base 10 alongside the body member 11 and beneath a sealing die 15. The band is held in desirable position on the base 10 and adjacent the body member 11 by means of a latch 16 the lowermost end portion of which engages the side of the band and which is in itself opposed by a coil spring 17. The uppermost end portion of the latch 16 extends above the body portion 11 so that it may be moved manually to permit the rethreading of the band in the banding tool. The band passes beneath the tightener roll 12 and emerges beneath the base as shown in Figure 2, passing through a slot like opening 18 which is formed in an extension 19 of the base 10. The band B, completing the loop of a size adapted to be positioned about a coil of strip steel, returns to the banding tool as indicated at B' and passes over the opposite end of the band directly below the sealing die 15. It is held in this position by the latch 16 and terminates after being placed in the slotted tightener roll 12.

It will thus be observed by referring to Figure 2 that when the tightener roll 12 is rotated in a clockwise direction the band B will be tightened with respect to the coil about which it has been positioned, the banding tool itself having served as a convenient handle for positioning the band about the coil, and at such time as the band B is tightened the slotted tightener roll 12 is held against backward rotation by means of a ratchet 20 (see Figures 1 and 3) at which time the sealing die 15 is depressed by means of a cam 21 formed on a transversely positioned shaft 22 which comprises the other one of the two rotatable shafts heretofore mentioned. The sealing die portion of the banding tool utilizes a mechanical principle well known wherein the cam 21 will, upon rotation of the shaft 22, engage the sealing die 15 and move it downwardly to effect a seal, it being desirable that a metal clip (not shown) as is commonly employed, be positioned about the band at the sealing point and the seal effected therethrough. In order that these two rotatable shafts may be rotated in carrying out the operations heretofore described in tightening and sealing the band, handles are affixed to these shafts, one of these, a handle 23, is pivoted about the slotted shaft 12 and provided with a ratchet 24 for engaging gear teeth 25 formed upon the slotted shaft 12. In connection with the ratchet 24 and the handle 23 there is a manual release lever 25' positioned through a portion of the handle 23 and operatively engaging the ratchet 24 so that the same can be released from engagement with the slotted shaft 12 which will then permit the handle 23 to be moved to the position indicated in dotted lines in Figure 2 of the drawing in which position a projection 26, formed on

the handle 23, engages one portion of an L shaped knife 27 and causes the same to move outwardly so as to cut the band B' which is being held under tension directly in front thereof. The knife 27 5 moves sidewardly and outwardly away from the body portion 11 of the tool and engages the band B' and cuts it from edge to edge. It has been determined that the band usually tears after the knife has entered from one side thereof and cut 10 a short distance. A spring 28 engages a section of the knife 27 and is adapted to return the knife 27 to its position within a slot-like opening in the body member 11 of the tool wherein the L shaped knife is pivotally positioned on a pivot 27A. It 15 will thus be observed that the tool effectively bands, tightens, seals and cuts in almost simultaneous operations, and further that the tool itself forms a convenient handle for supporting the loop form of the band in placing it about the coil 20 or strip steel to be banded.

The banding tool has been designed so that it may also be used in banding flat packages as, for example, packs of steel sheets about which the bands are applied to form an effective and efficient shipping package. In order to accomplish this purpose and provide an efficient tool having a base of sufficient length to insure against the tool's tipping during the tightening operation, the base, as may be seen in Figures 1 and 2 of the drawing, has outwardly extending projections 19 and 19A formed thereon in which slot-like openings 18 and 18A permit the passage of the band as in the operation of a banding coil as shown in Figure 2 whereas in utilizing the banding tool 25 in banding flat surfaced packages the band would remain above the extensions 19 and 19A of the base 10 so as to be on a substantially flat plane with respect to the flat plane of the surface of the rectangular package being banded. The operation in either case is substantially the same, as the band must be tightened through the rotation of the slotted shaft 12 and the seal must be effected by the sealing die 15 and the band subsequently cut by the knife 27. As illustrated in 30 Figures 1 and 2 of the drawing, the sealing die 15 comprises a U shaped member of an interchangeable character held in elevated relation with respect to the band passage therebeneath by means of a spring tensioned member 29 which 35 slidably engages the shaft 22 and the cam 21. The shaft 22 is adapted to be moved by means of a handle 30 as illustrated, which is the other one of the two handles heretofore mentioned.

Having thus described my invention, what I claim is:

1. In a banding tool including a base having a body member positioned thereon, a shaft having a portion extending longitudinally thereof, a second portion pivoted to said shaft and spaced slightly from said extending portion, the pivot thereof lying at a right angle to the said shaft, the said second portion adapted to be swung open so as to provide means for positioning a band to be tightened therein, means for rotating the said shaft comprising a handle and a ratchet adapted to engage teeth formed on the said shaft, a recess formed in the said body member adjacent the said shaft and into which the said hinged portion of the shaft may be manually moved when the said shaft is in an appropriate position, the said recess adapted to permit the hinged section of the shaft to be swung outwardly to approximately right angles to the remainder of the said shaft when said shaft is in said position, and

to close the hinged portion of the said shaft when the same is revolved out of said position.

2. In a banding tool including a base having a body member positioned thereon, a partially slotted shaft having a portion extending longitudinally thereof, a second portion pivoted to said partially slotted shaft and spaced slightly from said extending portion so as to form an extension of the said slot, the pivot thereof lying at a right angle to the said shaft, the said second portion adapted to be swung open so as to facilitate positioning a band to be tightened in the said slot, means for rotating the said shaft comprising a

handle and a ratchet adapted to engage teeth formed on the slotted shaft, a recess formed in the said body member adjacent the said slotted shaft and into which the said hinged portion of the shaft may be manually moved when the said shaft is in an appropriate position, the said recess adapted to permit the hinged section of the shaft to be swung outwardly to approximately right angles to the remainder of the said slotted shaft when said slotted shaft is in said position, and to close the pivoted portion of the said slotted shaft when the same is revolved out of said position.

CHARLES T. FISHER.
